UNITED STATES PATENT OFFICE.

JESSE WORBOIS, OF NORTH CHILI, NEW YORK, ASSIGNOR OF ONE-HALF TO CHARLES H. ROBERTSON, OF ENUMCLAW, WASHINGTON.

SORTING MACHINE.

Application filed September 26, 1923. Serial No. 665,010.

To all whom it may concern:

Be it known that I, JESSE WORBOIS, a citizen of the United States, and resident of North Chili, in the county of Monroe 5 and State of New York, have invented certain new and useful Improvements in Sorting Machines, of which the following is a specification.

The present invention relates to sorting 10 machines and an object thereof is to provide a machine which may be used for removing from plums and other articles, extraneous matters such as dirt, leaves and the like, as well as under-sized pieces of the 15 material to be sorted. A further object of the invention is to provide an improved feeding and agitating means for the material on the sorting table. Another object of the invention is to provide an improved 20 means of supporting the sorting table so that the inclination thereof may be varied. A further object of the invention is to combine with a sorting machine a crating mechanism which will operate in timed relation 25 to the sorting machine. A still further object of the invention is to make provision whereby the sorting machine and the crating mechanism may operate in timed relation and will be independently controllable so 30 that either one may be stopped independently of the other. Still another and further object of the invention is to combine with a sorting machine a crating mechanism which will feed the crates past the discharge of 35 the sorting machine and will, at the same time, agitate the crates so that the material will be compactly packed therein.

To these and other ends, the invention consists of certain parts and combination of 40 parts, all of which will be hereinafter described; the novel features being pointed out in the appended claims.

In the drawings:

Fig. 1 is a side elevation of a machine constructed in accordance with this invention; 45 Fig. 2 is a plan view;

Fig. 3 is a side elevation opposed to that side shown in Fig. 1;

Fig. 4 is a vertical section through the 50 machine with the crating mechanism removed;

Fig. 5 is a section on the line 5—5, Fig. 4; Fig. 6 is a section on the line 6—6, Fig. 4; Fig. 7 is an enlarged fragmentary vertical

section through the crate feeding mechanism; and

Fig. 8 is an enlarged sectional view of the clutch.

In the illustrated embodiment of the invention there is embodied a main frame 60 comprising, in this instance, four uprights 1, each two of such uprights being connected by a side board 2 at their upper ends, the two side boards being connected by an end board 3. Braces 4 connect the uprights 1 65 on each side, and the uprights on the two sides are connected at their lower ends by cross pieces 5.

On the main frame is a shaft 6 which is journaled upon the front uprights 1 at 7 70 and is driven in any suitable manner as by a bevelled gear 8 meshing with the bevelled gear 9 on a shaft 10 which has a worm wheel 11 thereon meshing with the worm 12 on a shaft 13, this shaft having a pulley 14 thereon over which passes a belt 15 connecting with a motor 16 supported on the main frame.

Mounted to rock upon the shaft 6 is a sorting table formed by side pieces 17, an 80 end piece 18 and slats 19, the slats being spaced apart to provide a slotted table. The table as a whole fits within the side pieces 2. In order that the table may be held at different inclinations about the shaft 6 as an axis adjusting means is provided comprising, in this instance, a rock shaft 20 journalled in the side pieces 2 and having two arms 21 which through links 22 connect with the upper end of the table. The shaft 20 is 85 controlled through an arm 23 which is held in different positions by a rack 24. It is apparent that the turning of the arm 23 will shift the sorting table about the shaft 6 as an axis so that the inclination of the table 90 may be varied.

For feeding the material downwardly on the table and at the same time for agitating such material so that the smaller material will drop through the slots of the table, 100 there is provided a feeding and agitating means, this comprising, in this instance, a rectangular frame 25 having cross bars 26 secured thereto, each cross bar having longitudinally extending series of projections 27 arranged to operate in the slots of the table, there being provided a sufficient number of bars so that the material on the entire 105

surface of the table is moved downwardly and at the same time is agitated. This feeding and agitating means has two movements, one to raise and lower the projections in the slots, and the other to move the projections longitudinally of the slots.

The mechanism for raising and lowering the projection in the slots embodies, in this instance, two shafts 28 and 29, each provided with cams 30 adapted to engage the under side of the feeding and agitating frame. These shafts may be rotated simultaneously by providing each of them on one end with a sprocket wheel 31 connecting such sprocket wheel by a sprocket chain 32. The shaft 28 has a gear wheel 33 which meshes with a gear 34 mounted to turn loosely on the shaft 6, as shown in Fig. 8, adapted to be connected to said shaft through a clutch member 35 which has projections 36 adapted to enter openings 37 in the gear 34. The clutch member 35 is keyed at 38 with the shaft 6 so as to turn with the shaft and at the same time to move longitudinally thereof. Movement of the clutch member 35 may be effected by a lever 39 which is pivoted at 40 to the side 2 of the main frame. It is apparent that through the movement of the lever 39 the up and down motion of the feeding and agitating means may be controlled either to stop or start the same. A bar 40^a extending across the main frame from the lever 39 to which it is pivoted at 41 may be employed for controlling the movement from the opposite side of the machine.

The movement of the projections longitudinally of the slots may be effected in any suitable manner but in this instance a link 41^a is pivoted at 42 to the under side of the feeding and agitating frame and is eccentrically pivoted at 43 to a disk 44 secured to the shaft 45 journaled on the main frame and having a gear 46 thereon meshing with the gear 47 on the shaft 29 so that the movement of the projections longitudinally of the slots will take place simultaneously with the up and down movement of the projections, the mechanism being so constructed and timed that the projections descend as they reach the lower end of the movement in the slots and ascend as they reach the upper end of the movement in the slots. It will also be noted that with the stopping of the up and down movement of the projections the stopping of the longitudinal movement of the projections also takes place.

The shaft 45 may be also used as a support for a take up device for the slack in the sprocket chain 32 and to this end an arm 48 is pivoted to the shaft 45 and has a sprocket 49 thereon meshing with the sprocket chain 32, a spring 50 connecting with the arm 48 and with the main frame and placing tension on the arm so that slack in the sprocket chain 32 is taken up.

Material which falls through the sorting table drops on an inclined chute 51 under it upon the main frame below the table, this chute being narrower than the table and having at opposite sides guiding surfaces 52 for directing the material to the chute. A guiding surface 52^a is provided at the end of the table for directing the material into the receiving chute at this point.

In order to insure the movement of the material directly on the chute an endless conveyor may be provided preferably in the form of a sprocket chain 53 passing about sprocket wheels 54 and 55 and arranged respectively at the lower and upper end of the chute. Extending transversely of this sprocket chain are slats 56 which travel upwardly and over the chute and downwardly under the chute, the material being discharged at the upper end of the chute. Movement of the endless conveyor of the receiving chute may be effected in any suitable manner but in this instance sprocket chain 57 connects with the shaft 58 on which the sprocket wheel 54 is mounted and also with a sprocket wheel 59 on the shaft 6 so that movement of the conveyor of the receiving chute is effected from the shaft 6.

Combined with the sorter is a crating mechanism embodying an endless conveyor upon which the crates 60 are placed, the endless conveyor positioning the crates so that the material discharged from the end of the sorting table will be received by the crates during their movement through the conveyor.

This endless conveyor embodies, in this instance, a frame 61 having sprocket wheels 62 mounted on shafts 63 and 63^a journaled on the frame 61. The sprocket wheels 62 are connected by two sprocket chains 64 which in turn are connected by bars or slats 65 to form an endless conveyor. At their ends these slats are guided on guide rails 66 so that the weights of the crates on the conveyor are taken up by the guide rails. Displacement of the crates from the conveyor may be prevented by rails 67 projected above and on opposite sides of the conveyor to cooperate with opposite ends of the crates.

In order that the crate moving conveyor may operate in timed relation to the sorting machine, the shaft 63^a is hollow and a shaft 68 extends therethrough being journaled at 69 on the main frame of the sorter and having a sprocket wheel 70 thereon which through a sprocket chain 71 connects with a sprocket wheel 72 on the shaft 10 hereinbefore mentioned. A clutch connection may be provided between the shaft 68 and the hollow shaft 63 in the form of a clutch member 73 on the hollow shaft 63^a and a clutch member 74 on the shaft 68, the clutch member 74 being keyed to the shaft 68 to turn therewith and having longi-

tudinal movement thereon so as to be moved in and out of connection with the clutch 73. A lever 75 pivoted at 76 controls the clutch member 74.

To the end that the material in the crates will be agitated during the movement of the crates past the sorter, an agitating means is employed in connection with the endless conveyor comprising, in this instance, a rock shaft 77 having an agitating arm 78 thereon. This arm lies over a rotary cam 79 on a shaft 80 which also has a sprocket wheel 81 thereon, this sprocket wheel connecting by a sprocket chain 82 with a sprocket wheel 83 on the shaft 63 so that, with the movement of the conveyor, the cam 79 will be turned and intermittently engage the agitating arm 78, causing the latter to cooperate with the slats 65 of the crate moving conveyor and agitate the latter, thereby causing the material in the crate to be packed more closely together.

The operation of the invention will be understood from the foregoing description but it may be summarized as follows:

Material such as plums are discharged on the sorting table near the upper end thereof and are carried downwardly toward the discharge end of the sorting table by the feeding and agitating fingers, the small plums, dirt, leaves and other extraneous matter falling through the slots of the table onto the chute below the table. The desirable plums are discharged from the table into the crates 60 which, travelling in timed relation to the sorter, become filled by the time that they reach the end of the crate-moving conveyor. The inclination of the table is varied to obtain the desired flow of the material and the agitating and feed-

ing means of the crate-moving conveyor may be stopped at any time independently of each other.

What I claim as my invention and desire to secure by Letters Patent is:

1. A sorting machine comprising a slotted table, a shaft on which said slotted table is mounted to turn so as to vary the inclination of the table, and agitating and feeding means operating in the slots of the table supported by the table to be adjusted therewith and driven from said shaft. 45

2. A sorting machine comprising a slotted table, a shaft on which said slotted table is mounted to turn so as to vary the inclination of the table, agitating and feeding means operating in the slots of the table supported by the table to be adjusted therewith and driven from said shaft, and means for adjusting the table on the shaft as an axis comprising a rock shaft supported on a fixed part and having arms thereon and links connected to said arms and to the table. 55

3. A sorting machine comprising a main frame, a shaft supported on said main frame, a slotted table adjustable on said shaft as an axis to vary the inclination of the same, a feeding and agitating frame having fingers operating through the slot 70 of the table, shafts supported by the table to move therewith about the first mentioned shaft as an axis and having cams cooperating with the table to move the fingers above and below the upper surface of the table, 75 said cams carrying shafts being driven from a shaft about which the table swings, and means for reciprocating the table also driven from the shaft about which the table swings.

JESSE WORBOIS.
